(No Model.)

F. M. GEORGIE, Sr.
CURTAIN AND SCREEN HOLDER.

No. 337,572.

Patented Mar. 9, 1886.

UNITED STATES PATENT OFFICE.

F. MORITZ GEORGIE, SR., OF CHATSWORTH, ILLINOIS.

CURTAIN AND SCREEN HOLDER.

SPECIFICATION forming part of Letters Patent No. 337,572, dated March 9, 1886.

Application filed May 26, 1885. Serial No. 106,687. (No model.)

To all whom it may concern:

Be it known that I, F. MORITZ GEORGIE, Sr., a citizen of the United States of America, residing at Chatsworth, in the county of Livingston and State of Illinois, have invented 5 certain new and useful Improvements in Curtain and Screen Holders, of which the following is a specification, reference being had thereto in the accompanying drawings.

10 My invention relates to an attachment for windows.

The object it has in view is to provide an attachment by the use of which a window-curtain may be left entirely free to be used as 15 a curtain, or may be converted into a window-screen, if desired.

To the accomplishment of the above the invention consists of a suitable frame so constructed and arranged that it may be turned 20 to occupy a position away from the curtain, which occupies a position between it and the window-frame, or may be turned to force the curtain against the window, thereby forming a perfect screen of such curtain.

25 Reference will be made to the accompanying drawings, in which Figure 1 is a front elevation of a window, showing the attachment away from the curtain; Fig. 2, a similar view with the curtain converted into a screen; Fig. 30 3, a side elevation of the attachment in the position shown in Fig. 1; Fig. 4, a detail perspective of part of the attachment; Fig. 5, a top plan, partly in section and broken away; Fig. 6, a cross-section through the window, 35 with parts shown in dotted lines; and Fig. 7, a detail sectional view of certain parts.

Like letters refer to like parts in each view.

In the drawings, A represents the window-frame; B, the window-sill; C, the window-40 sashes, and C' the curtain.

In carrying out my invention I prefer to use a curtain formed with an open mesh, whereby the air may be admitted when it is converted into a screen without admitting flies, &c.

45 Secured to each of the four corners of the window-frame by suitable screws is a bracket, D, between the arms a' a' of each of which there it pivoted an arm, E. Each of the brackets D is cut away on its under side, as clearly 50 shown in Fig. 7, and a leaf-spring, b', is secured thereto, the free end of which occupies

a position in close proximity to the inner enlarged end, c, of the arm E. The arms E of the lower brackets are bent slightly, as shown in Fig. 4, in order that they may be free in 55 their movements, and at the same time occupy positions near the window-sill when in the position shown in Fig. 4; but the arms of the upper brackets are preferably straight.

To the free end of one lower arm, E, there 60 is secured a horizontal tube, F, while to the opposite lower arm a similar rod, G, is secured, said rod being adapted to enter and move in the tube F, as will be described, the upper 65 arms being likewise connected. The upper and lower arms are connected in pairs on the same side of the window by vertical rods or tubes H. I have shown these several rods and tubes as inserted into rings K, secured to arms E; but it will be apparent that they may be 70 connected in any suitable manner.

The manner of using the attachment is as follows: When it is desired to use the curtain as a curtain, the several arms E are turned to the position shown in Figs. 1, 3, 4, and 5, when 75 the frame formed of the several tubes and rods is entirely free from the window-frame and curtain, and the latter may be moved as desired, the springs b serving to hold the parts in position. When it is desired to convert 80 the curtain into a screen, said curtain is drawn down to the position shown in Fig. 2, and the arms E turned on their pivots to occupy the position shown in Figs. 2 and 6, whereby the several rods and tubes will press against the 85 curtain and hold it in place, the springs b again serving to hold the parts in position.

As the frame is turned from the first to the second position, it will be understood that the rods G and tubes F will act as a telescope, 90 moving one within the other, and allowing of the change in position of the parts.

The several parts of the frame may be formed of any suitable materials and of any desired form and ornamentation.

What I claim is—

1. The combination, with brackets secured to a window-frame and arms pivoted therein, of rods and tubes connecting such arms, as set forth.

2. The combination, with brackets secured to a window-frame, arms pivoted therein, and

springs arranged to act upon such arms, of rods and tubes connecting such arms, as set forth.

3. The combination, with brackets D and arms E, pivoted therein, of rods G, tubes F, and rods or tubes H, as set forth.

4. The combination, with brackets D, arms E, and springs *b*, of rods G, tubes F, and rods or tubes H, as set forth.

In testimony whereof I affix my signature in to presence of two witnesses.

F. MORITZ GEORGIE, SR.

Witnesses:

M. J. CLAGETT,
FRANK S. BLANCHARD.
